UNITED STATES PATENT OFFICE.

ARTHUR MARICHAL, OF PHILADELPHIA, PENNSYLVANIA, ASSIGNOR TO THE
SOUTHWARK FOUNDRY AND MACHINE COMPANY, OF SAME PLACE.

VALVE.

SPECIFICATION forming part of Letters Patent No. 573,607, dated December 22, 1896.

Application filed May 27, 1893. Serial No. 475,689. (No model.)

To all whom it may concern:

Be it known that I, ARTHUR MARICHAL, a subject of the King of Belgium, residing in Philadelphia, in the county of Philadelphia, 5 in the State of Pennsylvania, have invented a certain new and useful Improvement in Valves, of which the following is a true and exact description, reference being had to the drawings which accompany this and which 10 form a part of the specification.

My invention relates to a novel construction of valves especially, although not exclusively, adapted for use with blowing-engines or compressors.

15 Rotary or oscillatory valves have heretofore been extensively used and in some cases applied to blowing-engines. Such valves have well-recognized merits, but especially in cases where large volumes of fluid are passed 20 through them they are subject to certain well-recognized drawbacks.

25 The object of my invention is to provide a valve system which will have the good features of the rotary valves heretofore used and in addition additional meritorious features due to my novel construction, the nature of which will be best understood as described in connection with the drawings, in which—

30 Figure 1 is a longitudinal section through the cylinder or tub of a blowing-engine, the upper part being taken through an admission-valve and the lower part through a delivery-valve. Fig. 2 shows, on an enlarged scale, a portion of the admission-valve, the section being the same as in Fig. 1. Fig. 3 is a 35 transverse section through the valve-seat on the line $x-x$ of Fig. 2. Fig. 4 is a perspective view illustrating the detachable connection between each valve and the valve-actuating 40 mechanism.

A indicates the blowing cylinder or tub of the engine; B B, the cylinder-heads.

45 C C C, &c., indicate a series of slotted openings or ports extending through the cylinder-head and forming a grid-valve opening.

D D D, &c., indicate cylindrical valve-seats formed in the head B and situated one in each of the slotted openings C.

50 E E E, &c., indicate rotary or oscillatory valves, one of which is situated in each cylindrical valve-seat D. These valves, as

shown, consist of two cylindrical portions E² E², seated in cylindrical cavities at each end of the slot C and connected by a segment-like bar E', which constitutes the valve 55 proper.

E³ indicates a valve-rod extending out from one end of the valve E and, as shown in Fig. 3, extending through a stuffing-box K, situated in a cast flange J.

60 The form of the valve-seat D should be such as will provide a cavity of substantially the same size as the segmental bar E' of the valve on one side of the slot C, so that when the valve is turned to open the slot C the 65 passage through said slot will be uninterrupted and of uniform section. It is also advisable, especially when my valve is used for a blowing-engine or pump, that the valve when closed should seat itself on the side of 70 the valve-seat through which the fluid enters the cavity of the valve-seat. Thus in the upper part of Fig. 1 it will be observed that the valve when closed seats itself on the upper part of the valve-cavity, as shown in the 75 drawings, or outer part relatively to the cylinder. As a result of this when air is compressed in the cylinder the valve is pressed tightly to its seat, while when the pressure 80 in the cylinder falls below the atmosphere there is a tendency to lift the valve from its seat. On the same principle, also, the valve shown at the lower part of Fig. 1, which is the delivery-valve, is made to seat itself on the inner portion of the valve-seat, or upper 85 portion, as shown in the drawings, owing to which construction the pressure of compressed air in the receiver indicated at L will tend to keep the valve seated, and the pressure of air within the cylinder when it exceeds the pressure in the receiver will tend 90 to lift it and make it easier to turn.

95 The series of cylindrical valves making up each admission and delivery valve are coupled with some reciprocating mechanism which will cause them simultaneously to open and close the respective slots which they control, and the connection with such reciprocating mechanism should in each case be independent and separable. In the drawings I have shown each valve of the series as 100 connected by means of independent lever-

arms F F, &c., with a transversely-extending bar G, which in turn is connected by a connecting-rod H with the arm I of a lever I I', pivoted at I², and to which motion can be imparted at proper intervals by any desired mechanism.

It is desirable that each rotary valve should be so connected with the valve-actuating mechanism that it can be disconnected at will, not only to permit the ready repair of each valve, but also so that in case of injury it can be left in a closed position while the other valves of the series are kept in operation. As shown, the lever-arms F are each detachable from the valve-rods E³ and the pins g of the bar G. Thus, as shown in Fig. 4, the lever F has a hole f at one end, which slips over the end of rod E³, while a hole f' at its other end slips over the pin g. The lever is firmly secured to rod E³ in any convenient way, as by a set-screw J, while of course it is free to turn on pin g.

Having now described my invention, what I claim as new, and desire to secure by Letters Patent, is—

1. In combination with a cylinder, a head B having formed in it a series of slots C forming a grid-valve opening, and a series of valve-seats D, one situated in each slot C, a

series of rotary valves E secured in the respective seats D, and means for simultaneously operating said valves to open or close the slots.

2. In combination with a cylinder, a head B having formed in it a series of slots C forming a grid-valve opening, and a series of valve-seats D, one situated in each slot C, a series of rotary valves E secured in the respective seats D, reciprocating mechanism, as bar G, for simultaneously actuating said valves, and a series of independent detachable devices as rods F for connecting the separate valves with the said reciprocating mechanism.

3. In a blowing-engine or compressor, the combination with a cylinder-head B having a series of slots C forming a grid-valve opening, and a series of valve-seats C one situated in each slot, a series of rotary valves E one secured in each slot and arranged to seat themselves across the slot on that side of the seat through which the air or gas enters the cavity of the valve-seat, and means for simultaneously actuating said valves.

A. MARICHAL.
